(57) **CLAIM**

The ornamental design for a charging holder for a vacuum cleaner as shown and described.

DESCRIPTION

1. Charging holder for a vacuum cleaner

1.1 : Front perspective view

1.2 : Back perspective view

1.3 : Front

1.4 : Back

1.5 : Left

1.6 : Top

1.7 : Bottom

1.8 : Front perspective view of a charging holder for a vacuum cleaner, shown in a state of use

This article is used for charging and placing a vacuum cleaner. A right view is omitted because it is a mirror image of the left view. The broken lines in reproductions 1.1 to 1.7 depict portions of the charging holder for a vacuum cleaner that form no part of the claimed design. The broken lines in reproduction 1.8 depict environment that form no part of the claimed design. The shading lines are used to show the surface of the claimed design and do not represent its surface ornamentation.

1 Claim, 8 Drawing Sheets
